UNITED STATES PATENT OFFICE

151,351

DESIGN FOR AN EXTERNAL DOME LIGHT FOR AUTOMOTIVE VEHICLES

Mathias J. Kately and Edward M. Peckwas, Chicago, Ill., assignors to Paul S. Ricchiuti, Chicago, Ill.

Application August 18, 1947, Serial No. 140,936

Term of patent 14 years

(Cl. D72—1)

To all whom it may concern:

Be it known that we, Mathias J. Kately and Edward M. Peckwas, citizens of the United States, residing at Chicago, in the county of Cook and State of Illinois, have invented a new, original, and ornamental Design for an External Dome Light for Automotive Vehicles, of which the following is a specification, reference being had to the accompanying drawing, forming part thereof.

Figure 1 is a perspective view taken substantially from the rear of the external dome light for automotive vehicles, embodying our new design.

Figure 2 is a perspective view taken substantially from the front of the device, as shown in Figure 1.

Figure 3 is a top plan view of the dome light, as shown in Figs. 1 and 2.

Figure 4 is a side elevational view of the dome light.

Figure 5 is a front elevational view of the dome light.

The characteristic features of our design reside in the portions shown in full lines.

We claim:

The ornamental design for an external dome light for automotive vehicles, substantially as shown and described.

MATHIAS J. KATELY.
EDWARD M. PECKWAS.
